WILLIAM FINN, OF NEW YORK, N. Y., ASSIGNOR OF ONE-THIRD TO LARS BENDIX
LARSEN, OF NEW YORK, N. Y.

KEY-LOCKING DEVICE.

No. 921,390.

Specification of Letters Patent. Patented May 11, 1909.

Application filed October 1, 1908. Serial No. 455,649.

To all whom it may concern:

Be it known that I, WILLIAM FINN, a subject of the King of Great Britain, and a resident of the city of New York, borough of Manhattan, in the county and State of New York, have invented a new and Improved Key-Locking Device, of which the following is a full, clear, and exact description.

The invention relates to door locks and its object is to provide a new and improved key-locking device for convenient attachment to the lock as a keyhole cover, and arranged to securely hold the key against turning from the outside and unlocking of the door by unauthorized persons.

The invention consists of novel features and parts and combinations of the same, which will be more fully described hereinafter and then pointed out in the claims.

20 A practical embodiment of the invention is represented in the accompanying drawings forming a part of this specification, in which similar characters of reference indicate corresponding parts in all the views.

25 Figure 1 is a face view of the improvement as applied and showing the members of the device locked but in an open position, for convenient insertion or removal of the key; Fig. 2 is an edge view of the same; Fig. 3 is an enlarged face view of the improvement showing the key in section and locked against turning by the device; Fig. 4 is an edge view of the same; and Fig. 5 is a face view of a modified form of the improvement.

30 The device, as illustrated in Figs. 1, 2, 3 and 4, is applied to the inside escutcheon A of a door lock B of any approved construction, and the device is in the form of a cover C pivoted at D to the escutcheon A above the 35 keyhole E, to normally cover the same and to engage the flat shank of the key F of the door lock B. The cover C is in the form of two arms C', C², mounted to swing from the pivot D as the center, and the opposite edges 40 of the said arms C', C² are provided with registering notches C³, C⁴, adapted to engage the flat shank of the key F, after the same is 45 inserted in the keyhole of the lock B, as indicated in Figs. 2 and 3, so that the key F is held against turning, especially from the outside, by unauthorized persons using suitable 50 tools for the purpose.

In order to hold the arms C', C² in a closed position, as shown in Fig. 3, or in an open 55 position as shown in Fig. 4, the following

arrangement is made: On the pivotal ends of the arms C', C² are formed two sets of notches C⁵, C⁶, of which the notches C⁵ are in register with each other when the arms C', C² are closed, while the notches C⁶ are then 31 out of register (see Fig. 3), and when the arms C', C² are opened the notches C⁵ are out of register while the notches C⁶ are in register. 36 The notches C⁵ are adapted to be engaged by a locking catch G fulcrumed on the arm C², 41 and the notches C⁶ when in register are adapted to be engaged by a locking catch G', likewise fulcrumed on the arm C'. Thus when the arms C', C² are in a closed position, the catch G engages the registering notches 46 C⁵, thus holding the arms C', C² against opening, and when it is desired to remove the key F, the catch G is swung upward out of engagement with the notches C⁵, to allow 51 swinging the arms C', C² apart for the removal of the key F (see Fig. 1). When the arms C', C² are in this open position, the catch G' engages the registering notches C⁶, to hold the arms C', C² in this open position, for the convenient insertion or removal of 56 the key F from the keyhole E. After the key is inserted and the door is locked, by turning the key, the flat shank thereof extends horizontally, so that when the operator now swings the catch G' out of engagement with the notches C⁶ then the arms C', C² close and the notches C³, C⁴ engage the flat shank of the key F, as indicated in Fig. 3. The catch G is now swung into engagement 61 with the registering notches C⁵, so as to hold the arms C', C² locked in a closed position.

From the foregoing it will be seen that when the arms C', C² are closed they cover the keyhole E, and at the same time hold the key F from turning by unauthorized persons.

In the modified form shown in Fig. 6, the device H for covering the keyhole E' and for locking the key against turning is provided with locking arms H', H² having notches H³, H⁴ similar to the device C shown in Figs. 1, 2, 3 and 4, and above described, the arms being mounted to swing on the pivot I held on the escutcheon J of the door lock. The pivotal ends of the arms H', H² are provided with radial arms H⁵, H⁶, between which is 103 adapted to pass a key K pivoted at K' on the arm H⁶, as shown in Fig. 5. Thus when the key K engages the arms H⁵, H⁶ the locking arms H', H² are held in a closed position, and when the key K is swung upward out of en- 108

gagement with the arm H^5 , as indicated in dotted lines in Fig. 5, then the locking arms H^1 , H^2 can be swung apart for the insertion or removal of the key K .

5 Other forms may be given to the device, which serves both a cover for the keyhole and a means for securely holding the key against turning by unauthorized persons.

Having thus described my invention, I 10 claim as new and desire to secure by Letters Patent:

15 1. A key-locking device, comprising a pair of locking arms mounted to swing on the lock casing, to normally cover the keyhole, the locking arms being provided on opposite edges with slots for engagement with the flat shank of the key to hold the latter against turning, and a device for holding the said arms in an open position.

2. A key-locking device, comprising a pair 20 of locking arms mounted to swing on the lock casing, to normally cover the keyhole, the locking arms being provided on opposite edges with slots for engagement with the flat shank of the key to hold the latter 25 against turning, the said arms being provided at their fulcrum ends with sets of notches, and locking arms for engagement with the said sets of notches.

In testimony whereof I have signed my 30 name to this specification in the presence of two subscribing witnesses.

WILLIAM FINN.
